UNITED STATES PATENT OFFICE.

JOHN DIXON HARPER, OF NEW YORK, N. Y., ASSIGNOR OF ONE-HALF TO BURNHAM W. KING,
OF NEW YORK, N. Y.

MUSICAL TOY.

No. 896,296.

Specification of Letters Patent.

Patented Aug. 18, 1908.

Application filed December 20, 1907. Serial No. 407,394.

To all whom it may concern:

Be it known that I, JOHN DIXON HARPER, a citizen of the United States, and resident of New York, in the county of Kings and State 5 of New York, have invented certain new and useful Improvements in Musical Toys, of which the following is a specification.

My invention consists of a new and improved musical device or toy, designed to be 10 blown by the mouth of the user, the same constructed and operated upon the principles hereinafter described and claimed.

In the accompanying drawings, to which reference is made and which form a part of 15 this specification: Figure 1 is a plan view of my new and improved musical toy. Fig. 2 is a sectional elevation of the same. Fig. 3 is a front elevation showing the front edge of the mouth piece.

20 In the drawings, 2 designates the tube or air chamber formed by preference of sheet metal, and in flaring or fan shape. To the narrower end of this tube or chamber is connected the mouth piece 3. This is formed of 25 the upper plate 4 in which there is a small hole or orifice 5, and the lower plate 6, in which is formed a corresponding small hole or orifice 7. The lower plate 6 is made in one 30 piece with or attached to the lower plate 8 of the tube or chamber, and is by preference slanted downward as shown in the drawings. Between the upper plate 4 of the mouth 35 piece and the upper plate of the tube or chamber 2 is left an opening 10, as shown clearly in Fig. 1. The upper plate 4 and the lower plate 6 of the mouth piece are, by preference, made of sheet metal and oppositely arched or curved to form the space between them, through which the breath of the user 40 is projected to produce sound or musical notes by the instrument, and in the mouth piece is secured a reed 12, as shown clearly in Fig. 2, having an orifice 9 located between the orifices 5 and 7.

45 The mouth-piece formed of the upper and lower plates is open through from end to end for the passage of the breath, the said opening through the mouth-piece to be controlled by the user. In this way the musical tone 50 produced can be modulated and easily controlled, for the reason that the user has full power over the use of the tongue and mouth in directing and controlling the breath as it passes through the instrument, much the 55 same as when whistling with the mouth and

lips alone. The tube or chamber is for magnifying the sound and carrying it out in greater volume.

Having thus described my invention, what I claim as new and desire to secure by Letters Patent is:

1. A musical instrument comprising a mouth-piece open from end to end, and formed of upper and lower plates, each provided with a small hole or orifice, substantially as described.

2. A musical instrument comprising a mouth-piece open from end to end, and formed of upper and lower plates, each provided with a small hole or orifice, and a horn 70 or chamber, to which said mouth-piece is attached, substantially as described.

3. A musical instrument comprising a mouth-piece open from end to end and formed of upper and lower plates, each provided with a small hole or orifice, said mouth-piece being provided with a reed across the center of the air passage thereof, substantially as described.

4. A musical instrument comprising a 80 mouth-piece open from end to end and formed of upper and lower plates, each provided with a small hole or orifice—said mouth-piece being provided with a reed across the center of the air passage thereof, 85 and located adjacent to the inlet end of the said air passage, substantially as described.

5. A musical instrument having a mouth piece composed of upper and lower plates spaced from each other to form an open passage between them, each plate having a small hole or orifice formed therein, in combination 90 with a reed held in the passage between said plates, said reed having a small hole or orifice formed therein, substantially as described. 95

6. A musical instrument having a mouth-piece composed of upper and lower plates spaced from each other to form an open passage between them, each plate having a small hole or orifice formed therein, in combination 100 with a reed held in the space between said plates, said reed having a small hole or orifice formed therein, and registering with the orifices formed in the said upper and lower plates, substantially as described.

7. A musical instrument comprising a mouth-piece composed of upper and lower plates spaced from each other to form an open passage between them, each plate having a small hole or orifice formed therein, and 110

a reed held in the space between said plates, said reed having a small hole or orifice formed therein, in combination with a horn or chamber attached to the said lower plate of the mouth piece, an opening being formed in the horn or chamber adjacent to the edge of the upper plate of the mouth-piece, substantially as described.

8. A musical instrument comprising a mouth-piece composed of upper and lower plates spaced from each other to form an open passage between them, each plate having a small hole or orifice formed therein, and

a reed held in the space between said plates, said reed having a small hole or orifice formed therein, in combination with a horn or chamber attached to the said lower plate of the mouth-piece, and slanted downward from said lower plate, an opening being formed between the said horn and the adjacent edge of the said upper plate of the mouth-piece, substantially as described.

JOHN DIXON HARPER.
